GRIPPING JAW FOR WIRE CLAMPS

Stephen P. Becker, Poughkeepsie, N. Y.

Application October 8, 1936, Serial No. 104,659

1 Claim. (Cl. 24—126)

My present invention relates primarily to a device for holding, splicing or securing one or more rods or wires together or to some object without the use of solder, welding, brazing or other permanent securing means, and which is largely employed to effect a solderless connection in electrical installation, and the invention relates more particularly to a novel form of gripping jaw or sleeve for holding the rod or wire, and of such design that it may be incorporated in a variety of different casings and used for a number of different purposes.

In the present construction as shown in U. S. Patent No. 2,041,108, and pending U. S. Patent application Serial No. 86,599, the jaws are in the form of separate pieces connected together by a follower, but this method of construction has been found expensive to make and assemble and the jaws being in parts do not always center the wire or move in unison, especially when being receded to release the wire.

To overcome these objections and to provide a universal jaw member for the purpose, and which can also be incorporated into wire and drill chucks and the like, I have devised the present invention.

The object of the invention is to provide a one-piece semi-resilient jaw-member capable of expansion and contraction within its predetermined limits.

Another object of the invention is to provide a one-piece jaw-member for wire connectors that shall be self centering within a casing or holder and upon the wire.

Another object of the invention is to provide a one-piece jaw member for wire connectors and clamps in which the wire may be inserted entirely through the connector or clamp thus allowing of "take-up" and adjustment.

A further object of the invention is to provide a one-piece jaw-member in which all of the gripping faces are always in perfect alignment and parallel relation with each other and with the wire.

A further object being to provide a one-piece jaw-member having a great resiliency and capable of use with either automatic or manually operated connectors or clamps.

With these and other objects in view, my invention consists in certain novel construction and combination of parts as will hereinafter be fully described and claimed and further illustrated in the accompanying drawing which forms a part hereof, and in which like figures of reference refer to corresponding parts in all of the views, and it

is understood that slight changes may be made without departing from the spirit of the invention.

In the drawing:

Figure 1 shows a side elevation of the one-piece jaw-member.

Figure 2 shows a rear end view of the same.

Figure 3 shows a longitudinal sectional view taken on the line 3—3 of Figure 2.

Figure 4 shows a longitudinal sectional view of a two-wire solderless connector, in which the jaw-members are employed, showing one of them in section, and the other of a modified form of construction.

Figure 5 shows a different form of two-wire connector or clamp, in which these jaw members 15 are employed.

Figure 6 is a partial view of one portion of a wire connector showing the method employed for receding the jaw-member to release the wire.

Figure 7 is a detailed side elevation of the preferred form of jaw member as employed in Figures 4 and 6, and illustrates how the position of the wire can be seen through the windows or openings therein when lined up with the openings in the casing.

Referring to the drawing:

The one-piece jaw unit comprises a tubular member formed with a straight exterior portion 10 parallel to its axis, and a tapered integral exterior body portion 11, of the desired taper to fit the casing within which it is mounted.

This one-piece jaw unit is formed with an axial bore 12 of the required diameter for the wire 16 that it is to be used upon, and the rear end is either counterbored as at 13 to retain one end of a tension spring 14 or may be shouldered upon the exterior, or left plain as desired; the outer or small end being slightly beveled as at 15 to facilitate entering the wire 16 therein.

To provide elasticity and render the unit semi-flexible and capable of self-expansion when released, and contraction upon the wire when forced into the tapered end of a casing, the unit is provided with a series of long longitudinal slots 17 open at the small end, and a second series of slots 18 closed on the inner ends and overlapping the long slots 17 and open at the large end of the unit, and thus by the removal of metal, the unit is rendered very flexible.

For gripping the wire 16, the interior bore of 50 the unit is divided into a series of gripping faces 19 by the long slots 17, and these jaw faces 19 are provided with transverse gripping teeth.

Referring to Figure 4, the one-piece jaw units are shown as mounted within a solderless wire 55

connector casing 21 having the interior tapered ends 22 and provided with an expanding coil compression spring 14 for normally retaining the units in extended relation within the casing and in holding relation with the wire 16; one unit being shown in section with the end of the spring 14 within a counterbore 13, and the other unit being shown with the end of the spring 14 within a counterbore in the end thereof.

10 Referring to Figure 5, a wire clamp is shown in the form of two members 23 and 24 having axial aligned tapered bores 25 and 26 within which are mounted a pair of the one-piece jaw units which are forced together and contracted upon the wires 16 by rotating the threaded portion 27 of the member 24 into the threaded interior portion 28 of the member 23.

15 Referring to Figure 6, the method for receding and holding the one-piece jaw unit so that it may expand and release the wire 16 is shown, and this 20 comprises an elongated hole 29 formed in the wall of the casing 21, through which may be inserted the point 20 of a rod or screw-driver to enter the closed end of one of the slots 17 and retain the unit in a receded and expanded wire 25 releasing position after having been pushed inwardly within the casing 17 by an inward movement of the wire 16.

30 As this type of one-piece jaw unit does not require a follower or other device for retaining the jaw members together, the wire 16 may be inserted entirely through the casing if desired, so that the clamp may be employed as a "take-up" for guy wires and the like.

35 The elongated holes 29 are formed in diametric relation to each other to afford an opening through which the location of the wire may be seen and also to provide a means for the drainage of water or dirt from the casing.

40 As shown in Figure 4, the one-piece jaw unit 10 may, in place of the parallel slots or cuts, be formed, adjacent to the large end with a series of radial openings 30 connected by a series of parallel slots or cuts 31 with the small end of the

unit thus providing a series of T-shaped slots rendering the unit flexible and self-expanding with the exception of the closed annular band 32. The openings 30 providing a ready means for the insertion of a rod or tool by which the unit may be receded against the action of the spring, while at the same time allowing the wire to be seen.

10 If it is not desired that the wire 16 be permitted to extend through the clamp, and only intended to be gripped near the end, it will be necessary to provide a stop for the end of the wire. This can be accomplished either by the use of a follower slidably mounted within the casing between the end of the tension spring 14 and the rear 15 end of the jaw unit 10, or as shown in Figure 4, by forming the ends of the tension spring 14 with cupped or conical ends 34 and adapted to be placed within the counterbored ends 33 of the jaw unit 10 thus providing a stop for the wire 16. 20

As shown in Figure 7, the jaw member is formed with the radial openings 30 communicating with the longitudinal cuts 31; the jaws thus formed being connected to the annular band 32 by the strips 35 which are slightly bowed or 25 bent outward and being of resilient material tend to exert an inward or compressing action on the jaws.

Having thus described my invention, what I claim is new and desire to secure by Letters 30 Patent, is:

In a gripping jaw including a compression spring, a clamp consisting of a band adapted to loosely surround the spring, resilient strips peripherally spaced about the band and extending 35 axially thereof, co-extensive spaced parallel wedge shaped gripping jaws each carried by a respective strip, said jaws being externally tapered inwardly away from said band, said jaws being thicker than the strips and extending radially inwardly 40 thereof to form in conjunction with said band and strips a cage for receiving a terminal of the spring.

STEPHEN P. BECKER.
